UNITED STATES PATENT OFFICE.

SAMUEL J. RILEY, OF YOUNGSTOWN, OHIO.

FURNACE REGULATOR.

Application filed July 30, 1927. Serial No. 209,436.

The present invention relates broadly to the art of heat responsive devices, and more particularly to a heat responsive regulator particularly adapted for use with furnaces.

It has heretofore been proposed to provide regulators of the general character herein contemplated for controlling the position of a damper or dampers, as well as the position of a suitable check valve for the draft. In so far as applicant is aware, however, such constructions have heretofore either been of such nature as to necessitate special provision for their accommodation during the design of the original furnace, or such as to involve difficulty in assembly with respect to the furnace and the available room present.

In the accompanying drawings there is shown more or less diagrammatically and for purposes of illustration only, a preferred embodiment of the present invention, it being understood that the drawings do not define the limits of my invention, as changes in the construction and arrangement disclosed therein may be made without departing either from the spirit of the invention or the scope of my broader claim.

In the drawings:

Figure 1 is a side elevational view of a furnace having my improved regulator in position thereon; and

Figure 2 is a detail sectional view on an enlarged scale, and partly broken away, illustrating the construction of the control mechanism.

In carrying out the present invention, there may be secured to one side of a suitable furnace 2, a bracket 3 having projecting therefrom a bearing 4 adapted to provide a pivotal mounting for a control lever 5. The bracket 3 is preferably secured to the furnace adjacent the upper portion thereof to permit the longer arm of the lever 5 to overlie the furnace in such manner as to normally extend substantially parallel therewith in a position in which it is protected from accidental movement or deformation.

The bracket, as clearly shown in Figure 2, comprises a body portion formed with an opening in which is secured one end of a tubular member 6 preferably of metal, of such composition as to have a relatively high coefficient of expansion. The furnace wall is drilled to accommodate the relative expandible member 6, a similar opening 7

being formed in the furnace wall on substantially a diametrically opposite side of the furnace. The free end of the relatively expandible member 6 projects through the opening 7 any desired extent, depending upon the relative length of the tube 6 and the diameter of the furnace, or the exact position or angle which the tube assumes relatively to a true diameter of the furnace.

The tube 6 on this free end carries a second bracket 8 internally threaded to cooperate with an adjusting screw 9 having an adjusting wheel 10 on its outer end. It will be understood that the wheel 10 may comprise an ordinary hand wheel, or that it may be provided with a groove 11 adapted to cooperate with a cable or other form of control, not shown, enabling adjustment thereof from a distance. Mounted within the tube 6 is a relatively non-expandible member 12 abutting at one end against the screw 9 and at the opposite end against a thrust block 13 engaging the control lever 5. By reason of this construction it will be apparent that by turning the adjusting screw 9 in such direction as to move the relatively non-expandible member 12 to the left, as viewed in the drawings, the pressure transmitted to the lever 5 will be increased, while by moving the adjusting screw in the opposite direction, the reverse condition will obtain. In this manner the exact temperature at which the parts become effective for moving the control lever may be regulated at will.

The control lever is preferably provided on its outer end with a roller 14 adapted to cooperate with a flexible actuating member 15, one end of which is secured to a projection 16 on the bracket 8, and the other end of which is attached to a damper 17. The flexible actuating member may also pass around suitable supporting pulleys 18 to a check valve 19, the connection being such that as the damper is opened to increase the draft, the check valve is closed for the same purpose.

The construction described lends itself to installation with existing furnaces since the control lever and the heat responsive elements may assume any desired position with respect to a true diameter of the furnace, the parts having such a length as to effectively operate in the manner intended when positioned to extend in line with the diameter of the furnace. Due to the fact that the

bracket 8 is not secured to the furnace but is free to float, any other arrangement of the parts necessary to accommodate varying features of construction, or to utilize in the most advantageous manner the room available, may be made.

Certain advantages of the present invention arise from the simplicity of the construction provided; from the shape of the control lever whereby it is adapted to overlie a furnace and extend throughout the major portion of its length, at least, in substantial parallelism to the heat responsive elements, and from the use of a mechanism requiring attachment at one point only to a furnace and adapted to extend through a furnace shell and project from opposite sides thereof.

Still other advantages arise from the provision of a regulating mechanism such that different arrangements thereof relative to a furnace, may be made as required by the exigencies of a particular installation.

I claim:

25. The combination with a furnace, of a bracket secured to the outer side wall thereof, adjacent the top of the furnace, a relatively expandible tubular member having one

end thereof secured to said bracket and of such length as to extend through a portion of the furnace in the horizontal plane of the bracket, a second bracket secured to said tubular member at its other end exteriorly and independently of the furnace, a relatively non-expandible member within said tubular member, adjusting means carried by said second bracket and engaging said relatively non-expandible member, a thrust block engaged by said relatively non-expandible member adjacent its opposite end, an L-shaped lever having a substantially vertically extending arm pivotally connected to said first bracket for engagement by said thrust block and having a substantially horizontally extending arm overlying the furnace and terminating above and substantially in the vertical plane of the second bracket, and a flexible actuating member secured at one end to said second bracket and engaged by the free end of said second mentioned arm for maintaining such free end during movement thereof in desired relation to the second bracket.

In testimony whereof I have hereunto set my hand.

SAMUEL J. RILEY.
